UNITED STATES PATENT OFFICE.

OTTO KARTZMARK, OF WEST HAVEN, CONNECTICUT.

DISPENSING RECEPTACLE.

Application filed June 21, 1922. Serial No. 569,890.

To all whom it may concern:

Be it known that I, OTTO KARTZMARK, a citizen of the United States, residing at West Haven, in the county of New Haven and 5 State of Connecticut, have invented certain new and useful Improvements in Dispensing Receptacles, of which the following is a specification.

This invention relates to receptacles or 10 storage retainers from which any suitable commodity, such as coal, grain, sand, lime, groceries, or other loose bulk articles are adapted to be dispensed from the bottom, and while this device has been constructed 15 and has been successfully used for the purpose of temporary storage and dispensing of coal for a kitchen range or the like in dwelling houses, I wish it to be understood that it is capable of a much wider range of use- 20 fulness as the title indicates.

Among the objects of the invention is to provide a receptacle of the nature indicated having a peculiarly arranged hopper bottom and delivery chute, the construction of which 25 renders it especially well adapted for the delivery of the last particle of material, the provision of a closure or door having new and peculiar co-operation with the chute portion of the hopper bottom whereby the 30 closure is free to swing through substantially a quarter of a circle around its horizontal pivot or axis so as to lie open for shoveling purposes or to be self retained in closed position, due to its over weight in 35 either position, but which is easily swung from either position to the other by a touch from the operator's hand or foot, and which also is of such a nature as to prevent the discharge of dust or dirt from the receptacle to the floor or any other part of the 40 building, and the construction furthermore has reference to a number of details of construction which tend to simplify, strengthen, and improve the device for practical purposes.

With the foregoing and other objects in view the invention consists in the arrangement and combination of parts hereinafter described and claimed, and while the invention 50 is not restricted to the exact details of construction disclosed or suggested herein, still for the purpose of illustrating a practical embodiment thereof reference is had

to the accompanying drawings, in which like reference characters designate the same parts 55 in the several views, and in which—

Figure 1 is a plan view with the chute closure open as in Fig. 2 and with a portion 60 of the lid broken away to disclose the hopper bottom.

Fig. 2 is a vertical longitudinal section on the line 2—2 of Fig. 1.

Fig. 3 is a front elevation of the lower part of the device, the closure being shut.

Fig. 4 is a side elevation of the chute and 65 closure members, parts being in section on the line 4—4 of Fig. 3.

Fig. 5 is a detail perspective view of the chute detached.

Fig. 6 is a detail perspective view of one 70 of the supporting legs.

Fig. 7 is a plan view of the blank from which the main hopper bottom is formed.

Fig. 8 is a plan view of the blank from 75 which the chute is formed.

Fig. 9 is a sectional detail of the chute frame or yoke, indicating especially the manner of hinging the closure thereto.

Referring now more specifically to the drawings I show a receptacle, the body of 80 which is of a generally rectangular form and comprises a front wall 10, rear wall 11, side walls 12, and a top having a stationary panel 13 and a lid 14 movable upward and rearward around an axis 15 adjacent to the 85 front edge of the stationary panel 13. The adjacent edges of these panels or walls may be secured together by any suitable means but which is indicated as comprising angle members 16 overlapping the several joints 90 and suitably secured to the several wall members. These angle members make a very rigid construction even though the material, such as sheet metal, from which the structure is made may be relatively thin or light. 95 The adjacent edges of the panels 13 and 14 are preferably stiffened or reinforced by the bending thereof around bars or plates of metal or the like, indicated at 17, and the front and side walls also may be bent over 100 as shown at 18 to stiffen the edges thereof that are exposed when the lid is open.

The supporting legs, of which I prefer to use one for each corner, are shown in detail at 19, Fig. 6, each comprising two 105 members of angle construction having

straight vertical portions rigidly and permanently secured together at 20 by rivets and with the upper ends thereof bent horizontally and at right angles to each other forming a seat 21 directly into which the adjacent corner portion 22 of the body rests with maximum strength and security, the weight of the receptacle coming directly upon the angle members, and the position 10 of the legs with respect to the body is maintained by any suitable fasteners such as rivets 23 passing laterally through the upstanding flanges of the legs. Moreover these legs present an unusually neat appearance 15 as well as being exceedingly strong and rigid. Supporting casters for these legs may be provided if desired for the usual purpose.

The main hopper bottom comprises a construction 20 made from the blank of Figs. 7 and includes a main rear panel 24, two side wings 25, two front wings 26, and a substantially horizontal front plate 27. The side wings 25 are bent at an obtuse angle 25 along the bending lines 28 extending from the rear corners of the bottom downward and forward to the rear corners of the plate 27 where they intersect the bending line 29 between said plate and the rear panel 24 30 and the bending lines 30 between the respective pairs of side and front wings. The wings 26 are bent upward and toward each other into approximately the same plane but with the inner points 31 thereof overlapping each other, see Fig. 1, thereby forming a delivery opening 32 of triangular form over and spaced from the plate 27 and through which the commodity to be dispensed will naturally flow or roll by gravity upon the plate 27. While this plate is approximately horizontal it is indicated in the drawings as being preferably inclined downward slightly toward the front to facilitate the delivery of the goods.

The chute portion of the bottom is made 45 preferably from a blank or pattern as shown in Fig. 8 and comprises a top panel 33 and two side panels 34, the latter being connected to the top panel along parallel bending lines 35. This top panel therefore is substantially rectangular but for a triangular notch 36 cut from its rear end and registering with the delivery opening 32 above described. In other words, the overlapping front wings 26 of the main bottom member substantially coincide with the remaining top portion 33 of the chute. This makes an exceedingly strong and rigid chute construction and with no possibility for any 50 of the material or dust to be discharged laterally therefrom. The bottom edges of the triangular side panels 34 are bent inward toward each other at 37, and above the upper surfaces of these flanges 37 is secured the plate 27, said flanges being

spaced just far enough below the top 33 of the chute to permit the plate 27 to slide into place during assemblage.

As a reinforcement for the front edge or mouth portion of the chute I employ a yoke 38, of substantial U-form as viewed from the front, having a horizontal portion and two upright portions whose upper ends are secured at 39 to the bottom rail 16 of the front wall 10. This yoke is strong and rigid 75 and directly embraces the front ends or edges of the side panels 34, and upon the upper surface of the yoke is supported the front end or edge of the plate 27.

The closure comprises a rectangular front 80 plate 40 with two parallel side wings 41 of substantially quarter circle form. The front or upper edge of the plate 40 strikes against the front portion of the just mentioned rail 16 while the side wings have 85 loose embracing engagement with the sides of the yoke 38, and the lower edge of the plate 40 rests or rolls like a knife edge upon the front end of the plate 27. Thus the closure opens and closes with practically no friction and this constant contact between the two plates 27 and 40 prevents any dust or other material from passing forward under the closure. Any suitable means may be provided to prevent the displacement of the closure from the yoke. As shown this means comprises a pair of ears 42 formed on the corner portions of the yoke, the upper free ends of which ears are bendable rearward toward the main portions of the side bars of the yoke forming 100 eyes 43. Said ears are projectable through holes 44 formed in the lower corners of the plate, these holes as well as the eyes 43 being large enough to insure free swinging 105 movement of the closure in either direction. From the normal closed position, as shown in Fig. 3, the closure may be swung forward by any suitable means, as by bearing 110 downward upon a lug 45 fixed near the bottom thereof. Thus the closure is swung forward until it passes the dead center and is finally stopped by a lug 46 formed at the upper rear end of either wing 41 which strikes against the bent portion 39 of the 115 yoke. See Fig. 4. To close the chute the operator has but to lift easily upon the plate 40 causing it to swing till stopped by striking the rail 16 as already stated.

From the foregoing specific description 120 of the mechanism illustrated its mode of operation may be briefly summed up as follows: The closure plate 40 being normally shut as in Fig. 3 the receptacle may be filled through the opening at the top after 125 the lid 14 is lifted, a portion of the coal or other material rolling or flowing downward through the registering openings 32 and 36 upon the plate or floor 27 of the chute but at no time pushing forward 130

- against the closure forcibly enough to open the closure. For removing the material through the chute the operator drops the closure plate 40 downward, as shown in 5 Figs. 1 and 2, and over this plate the shovel or the like may be operated rearward beneath the bulk of material upon the plate 27, the shovel being readily filled thereby and removable over the closure. 10 Any loose particles of the material dropping from the shovel will be received upon the plate 27 or plate 40 and between the wings 41 thereof. After the operation is completed the closure is lifted and the wings 15 thereof swinging rearward beyond the vertical plane of the axis constituted by the lower edge of the plate 40 pass freely along the outer sides of the chute walls 34 and will hold the plate 40 shut.
- 20 I claim:
1. In a receptacle of the nature set forth, the combination of a main body having a hopper bottom with an opening therein through which the material is adapted to flow, a 25 chute extension for the bottom surrounding said opening and having a bottom plate constituting a portion of the aforesaid bottom structure beneath said opening, and a closure for the chute extension, said closure comprising an outer plate and two side wings connected thereto, means being provided to attach the closure to the chute structure for movement of the closure around a horizontal axis in direct contact with said 30 plate.
  2. A device as set forth in claim 1 in which the front mouth portion of the chute includes a reinforcing yoke and the means for attaching the closure for swinging movement includes members formed as parts of said yoke.
  3. A receptacle as set forth in claim 1 in which there is provided a reinforcing frame for the mouth of the chute and the closure is 45 connected to said frame for swinging around a horizontal axis, and stop means is provided acting between the closure and the frame for limiting the forward swing of the closure into open position.
  4. In a dispensing receptacle, the combination of a bottom structure including a plate and a chute, a reinforcing frame bounding the mouth portion of the chute, the front end of the bottom plate resting 50 upon the frame, the frame being provided with a pair of ears adjacent to said bottom plate, and a closure for the chute comprising a plate portion whose lower corners are interengaged with said ears and whose lower edge bears consequently upon the upper surface of the plate.
5. A receptacle as set forth in claim 4 in which the closure includes a pair of parallel side wings each of substantially quarter circle form and having stop means at the rear corner thereof to limit the forward swing of the closure. 65
6. A receptacle as set forth in claim 4 in which the closure includes a pair of side wings of arc shape and of a radius shorter than the height of the closure plate, the portion of the plate extending above the side wings striking rearward against the main structure to limit the swing thereof rearward. 70
7. In a dispensing receptacle, the combination with a main body, of a hopper bottom structure therefor including two triangular shaped front wings arranged in substantially the same plane but with portions thereof overlapping forming a discharge opening through the hopper bottom, and a chute extension below said opening, said chute extension including a top panel and side wings, said top panel having a recess coextensive and registering with the opening aforesaid in the hopper bottom. 80
8. A receptacle as set forth in claim 7 in which the hopper bottom structure includes a plate extending forward of and below the discharge opening and upon which the material is received through said opening, and the chute structure includes side panels co-operating with the side edges of said plate extension. 90
9. A receptacle of the nature set forth including a substantially rectangular body portion, supporting legs for said body, each leg having a substantially vertical portion of rectangular form in cross section and having at its upper end two angle members extending horizontally and diverging from each other at a right angle forming a seat for the adjacent corner of the body, the weight of the body coming directly upon the flanged structure of the legs. 100
10. A receptacle of the nature set forth including a substantially rectangular body portion, supporting legs for said body, each leg composed of two angle members assembled to form a rectangular portion while the upper ends diverge from each other at right angles and with two vertical and two horizontal flanges, the vertical flanges being on the outside of the corner portion of the body 105 supported and embraced thereby.

In testimony whereof I affix my signature.
OTTO KARTZMARK.
